UNITED STATES PATENT OFFICE.

JOHANNES KARL RUTHS, OF DJURSHOLM, SWEDEN, ASSIGNOR TO AKTIEBOLAGET
VAPORACKUMULATOR, OF STOCKHOLM, SWEDEN.

METHOD OF SHORT-TIME DIGESTING IN SULFITE OR SULFATE DIGESTERS.

1,368,577.

Specification of Letters Patent.

Patented Feb. 15, 1921.

Application filed March 10, 1919. Serial No. 281,704.

To all whom it may concern:

Be it known that I, JOHANNES KARL RUTHS, subject of the King of Sweden, residing at Djursholm, Sweden, have invented 5 certain new and useful Improvements in Methods of Short-Time Digesting in Sulfite or Sulfate Digesters, of which the following is a specification.

In my Patent No. 1,292,080, granted to 10 me on Jan. 21, 1919, an arrangement is described by means of which the total time for treating a batch in sulfite boilers may be reduced by a shortening of the steaming period, an equalization of the variations 15 in load occurring in the boiler house being obtained at the same time.

My present invention relates to an improvement for obtaining a further considerable increase of the advantages gained by 20 an arrangement according to the above-named patent.

Whereas according to the above-named patent a saving of time could be obtained only by a shortening of the so called steaming process, according to the present invention the same method has been applied also to the carrying out of the digesting *per se*. Figure 1 in the accompanying drawing shows the principle of carrying out my 30 new method. Fig. 2 is a boiling diagram; Fig. 3 is a diagram to illustrate my new method applied to a plant with four digesters.

S is the quantity of steam required for 35 the steaming, and B denotes the quantity of steam required for the digesting. The digesting takes place in the following manner. In the period between the steaming and the starting of the digesting process the acid 40 required for the digesting is run into the digesters, said acid absorbing the heat imparted to the chips so that the temperature of the acid is somewhat increased. In most cases this temperature will be about 45 50° at the time a. At the end of the digesting period, *i. e.*, at the point b, the temperature of the acid generally amounts to about 140°.

The chemical process in the boiler only 50 commences upon the acid having reached the temperature of about 108°, at the point c. The time a-c is called the starting period of the boiler, while the time c-b corresponds to the true time of boiling.

55 If it is now desired to reduce the time a-b

required for the whole boiling period, it is evident that such a reduction may be effected only during the time a-c, a reduction of the time c-b causing an impairment of the quality of the mass, or great losses. 60

It is assumed that the present case pertains to a so called indirect boiling, *i. e.*, the heat of the steam is transmitted to the acid by means of tubes. It is to be observed, however, that the principle of the invention 65 may also be applied to indirect boiling, the same being obviously independent of the carrying out or not of a steaming process previously to the boiling.

In indirect boiling the line d-e shows 70 how the pressure of the boiler is nearly maintained. As will be seen, the pressure in the starting period increases comparatively rapidly up to the maximum pressure allowed, or generally 4 to 6 kilograms above 75 atmospheric, this pressure being then maintained constant by distillations during the entire boiling process. It will be seen from the diagram that the boiler pressure is increasing much more rapidly than the corresponding saturation temperature of the water, this depending on the quantity of free sulfurous acid accumulating in the upper part of the boiler and increasing the pressure. 80

Whereas heretofore steam of constant pressure has been always used corresponding nearly to the maximum pressure of the boiler, or about 6 kilograms for the carrying out of the entire boiling process, this 90 method aims at the employment of steam of a considerably lower pressure during the starting period. This steam is taken from the steam accumulator mentioned in the above-named patent, and the same consequently falls in the course of the process. An equalization of the steam impulses being thus obtained between the boiler house and the boiler by the use of the steam accumulator, the quantity of steam B supplied during the starting period may be chosen considerably higher than at present, the time being thereby reduced in a corresponding degree. 95

Obviously, not the pressure in the boiler 105 but the difference in temperature between the steam at the instant of condensation and the temperature of the acid is decisive for the transfer of heat between the steam in the tube and the acid in the boiler. 110

Now, in many cases, it will be found that with the present arrangement it is not possible to force a sufficient quantity of steam through the tubes, these having been dimensioned for relatively small quantities of steam with regard to the boiler house. As is well known, however, the drop in pressure in a steam conduit with a certain quantity of steam is inversely proportional to the 5th power of the diameter, only a small increase of the latter thus being sufficient to enable the forcing of a considerably larger quantity of steam through the tube than at present without exceeding a very small drop in pressure. At the same time the pressure in the tube along the entire length thereof is kept about the same as the initial pressure, whereas under the conditions hitherto prevailing the pressure is apt to fall rapidly. Thus, the average temperature of the tube becomes considerably higher, if the diameter is somewhat increased.

Fig. 2 illustrates the appearance of the boiling diagram when using the arrangements suggested above. S again corresponds to the quantity of steam requisite for the steaming operation, a—c being the starting period; the diagram for the boiling time proper, c—b, is the same as before. In Fig. 2 it is assumed that during the first period of the boiling, while the pressure in the boiler is still low, a quantity of steam T is admitted directly into the acid, in addition to the steam admitted into the tubes.

Fig. 3 indicates how this method is working as applied to a plant with four boilers and with a total time for treatment, which from the original of 20 hours has been reduced to 17 hours by the present invention.

In the diagram the bottom load represents the quantity of steam requisite for the completing of the boiling, the tops partly giving the quantities of steam for the steaming operation, and partly the quantity of steam required for the starting up to 108°. K shows the quantity of steam delivered from the boiler, and, as will be seen in the present case, a complete equalization of the same is taking place, the working of the boiler being thereby rendered practically uniform.

The accumulator is charged during the time a—b, discharged during the time b—c, charged anew during the time c—d and dis-

charged during the time d—e, charged again during the time e—f and so on. The charging condition of the accumulator is indicated in the upper part of the diagram. 55

By extending the method set forth in the above-named patent as indicated, a further considerable shortening of the treating time 60 for the boilers, or an increase of the output of the plant may be obtained by the arrangements described in the above-named patent. While on one side, only about 50 minutes to an hour could be saved by steaming from the accumulator alone, on the other side an estimation of the present case will show that as much as three hours may be saved, which with an original treating time of 19 hours brings about an increase in the 70 output of the plant of not less than 19%. Thus, in many cases the output of a sulfite plant with 5 or more boilers will be increased in the same degree by the installation of a steam accumulator as by the installation of a new boiler; as in the first case it will not be necessary to enlarge the boiler house, the old one answering its purpose and being, moreover, considerably unloaded, it is evident, that the capital for a plant 80 with an accumulator will be considerably less than the capital required for any other enlargement, great savings in steam and coal being obtained in addition thereto. 75

Obviously, the views demonstrated above 85 pertain also to a so called basic boiling of cellulose (sulfate plant), independently of steaming being used or not as well as independently of whether direct or indirect steam is employed for the boiling. 90

Claim:

The method of short-time digesting in sulfite or sulfate digesters, which consists in effecting both the steaming and the starting operation with steam of low pressure obtained from an accumulator connected with the digester, and then completing the digesting operation with steam of higher pressure as supplied by the steam generating plant. 100

In testimony whereof I affix my signature in presence of two witnesses.

JOHANNES KARL RUTHS.
